MEANS FOR MAKING SLACK STITCHING

Antonio Turrisi, New York, N. Y., assignor to
 Maiden Form Brassiere Company, Inc., New
 York, N. Y., a corporation of New York

Application March 10, 1938, Serial No. 195,065

9 Claims. (Cl. 112—179)

This invention relates broadly to new means for making slack stitching.

This application co-pends with my application Serial No. 347,399, and my application Serial No. 5 347,400, each of which was filed July 25, 1940, under the title: "Method of and means for making stitched open work," as a division hereof.

One of the objects of this invention is the provision of a novel false hemstitching device for 10 use in the stitching together of fabric portions with a line of slack stitch.

Another object of this invention is the provision of simple, practical, rugged and economical means adapted to ready embodiment in existing 15 standard sewing machine constructions, after the embodiment of which, such sewing machine constructions may be utilized to stitch together fabric portions with a line of loose or slack stitch.

Another object of this invention, is the provision of economical, convenient and readily useable apparatus for so uniting fabric portions by slack stitching, that when said fabric portions subsequently are suitably treated and again stitched they are joined by a practical, rugged, 25 useful and ornamental stitched open work.

A still further object of this invention is the creation and provision of such novel apparatus and parts as I have found are beneficial and/or desirable towards production of the resulting 30 desired ornamental stitched open work.

These and many other objects are secured by the invention hereinafter disclosed. Various further and other objects and advantages of the invention other than those hereinabove specifically mentioned, will appear more fully hereinafter.

It is to be understood that the specific forms shown in the accompanying drawings are merely 40 illustrative, and hence the description thereof is not to be taken as limiting.

This invention resides substantially in the parts, as well as in the combination, construction, arrangement and relative location of parts, all as will appear more fully hereinafter.

Referring to the drawings, wherein like reference numerals are used throughout the several views to indicate the same or similar parts, it will be found that:

Fig. 1 represents a side elevational view, partly 50 sectional and with some parts broken away, of a sewing machine provided with one of the features of my invention and shown with two fabric sections in work position between presser-foot and throat plate;

Fig. 2 is a sectional view taken along the bro-

ken sectional line 2—2, in Fig. 1, looking in the direction of the arrows; with certain parts shown in elevational view;

Fig. 3 is a top plan view of a broken away portion of the sewing machine throat plate showing how my novel hook element or stitch finger, mounted on and carried by the sewing machine bobbin case holder, is configured and positioned with respect to the throat plate;

Fig. 4 represents a broken away view showing 10 a longitudinal section of the work and illustrating the appearance of the slack or loose stitches as the work is delivered from the machine and further shown with some of the needle thread loops in a position surrounding the bobbin thread 15 and my novel hook or stitch finger element above mentioned;

Fig. 5 represents a broken away partially side perspective view showing the beak of the rotary hook shortly after having picked up a loop of 20 the needle thread; with a portion of the work shown in section; and with needle omitted;

Fig. 6 represents a view similar to that of Fig. 5, except that the beak of the rotary hook is shown in position after having been revolved to 25 a point where a limb of the needle thread has been passed and looped over the bobbin thread;

Fig. 7 represents a view similar to those of Figs. 5 and 6, but showing the beak of the rotary hook in a position shortly after the needle thread 30 loop has slipped out of and been discharged from the beak and has been partially drawn in;

Fig. 8 represents a front elevational view of a bobbin case holder showing a modified form of my novel hook or stitch finger carried at the 35 top thereof;

Fig. 9 represents a top plan view of the element shown in Fig. 8, with part of such element broken away; and

Fig. 10 represents a top plan view of a broken 40 away portion of the form of throat plate which may be used in conjunction with the form of my novel hook or stitch finger shown in Figs. 8 and 9; said hook or finger being shown in plan in this figure.

As is well known, numerous efforts have heretofore been made from time to time to create and provide a relatively simple, cheap, rugged and easily embodyable apparatus for use in sewing machines for joining fabric sections together by 50 a line of slack stitching readily convertible into practical, rugged, useful and ornamental stitched open work. Thus, in the art of sewing, it is often highly desirable to join two fabric portions together with ornamental stitched open 55

extends upwardly and is preferably bent near its base at 21 so as to completely clear all portions of the rotary hook 5, and after clearance, is 5 reversely bent at 22, so as to again approach, yet stop short and clear of the line of action that the needle 3 follows and the various positions it assumes when passing through the work piece. The hook 20 thereafter continues upwardly until the plane of the throat plate 23 is substantially 10 reached and it there, at the uppermost part of said element 20, lies just under the work and a slight distance to one side of the point where the needle pierces the work; in other words, the hook or finger element 20 extends substantially up into 15 the general plane of the throat plate 23. At the throat plate 23, the element 20 is again bent at 23a and extends rearwardly along a line parallel to the presser-foot 2, the work, and the line of stitch being formed therein; providing an extension 20 of said element 20, extending rearwardly a sufficient distance, so that a few stitches may be held thereon as hereinbefore described. From an examination of Fig. 3, it will be understood that the finger 20 is so shaped and positioned 25 that when substantially in the general plane of the throat plate 23, it will not interfere with, but will rather lie clear of the line of action of the needle 3 and the feed dog 25. An inspection of Fig. 3, will disclose that in order to as closely as 30 possible approach the line of stitch, yet clear the needle 3, that it may be found preferable to further bend the portion 24 slightly as at 26. It will be understood that it is always desirable that the portion 24 lie as closely parallel to the line of 35 stitch as is possible if not exactly thereunder; and hence by bending the portion 24 at 26, the free end portion of 24 is brought substantially into a line directly under, or, closely adjacent to a line directly under, that of the line of stitch, while 40 the needle 3 is cleared. It should be still further understood that I provide my throat plate 23 with such appropriate openings 27 therein, as are necessary to accommodate the serrated portions of a feed dog 25. I also provide sufficient room and 45 space for the portion 24 of the finger element 20, and this necessitates, besides the throat plate openings 27, an opening, 28, of the character illustrated in Fig. 3. Having thus described the construction which I have shown in Figs. 1 to 3, 50 inclusive, I will now briefly describe the manner of the utilization thereof.

Thus turning to Figs. 4 to 7, inclusive, it will be observed that I show in Fig. 4 two portions of fabric, to wit, an upper portion 29 and a lower portion 30, being secured together by a line of slack stitching. In Fig. 4, the thread 31 is the needle thread and the thread 32 is the bobbin thread, and this figure of the drawings shows how loops of the needle thread 31 are, in my device, engaged about the portion 24 of the finger 20 and the bobbin thread 32. Likewise, this figure shows a number of slack loops in engagement with the bobbin thread after such loops have slipped off the free end of portion 24 of the finger 20, upon 60 feed of the work from right to left in said figure. Turning next to Fig. 5, for an understanding as to the operation of my invention, it will be understood that the position of the parts there shown is that shortly after the beak 6 of the 65 rotary hook 5 has picked up a loop of the needle thread 31, and which beak, upon rotation, will carry such loop down and to the left. Four already-formed loops are shown, two of them after having left the free end of portion 24 of element 70 20, two of them still wrapped around portion 24

of element 20; and with the bobbin thread 32 shown engaged with all four loops.

In Fig. 6, the needle thread loop has been carried by the beak 6 to a point where the needle side limb 31a of the needle thread 31 has been 5 looped and thrown over the bobbin thread 32, while the work-side limb 31b, of the needle thread loop, remains behind the bobbin thread.

In Fig. 7, the beak 6 of the rotary hook 5 has been rotated to a point where the needle thread 10 loop has been discharged from the beak 6 and the needle thread loop is being diminished by retraction upwards of the needle and the upwards action of the customary sewing machine thread take-up lever. As the needle thread loop is drawn 15 in, the portion of the thread forwardly of the portion 24 of element 20, is pulled generally upwards and slides over the external surface 13 of the lug 11 which acts as a thread guide, and the thread passes the same and continues up through 20 the depression 12, in the bobbin case holder 7; and said loop is gradually brought to snugly wrapped-around position about the portion 24 of the element 20 and into a condition similar to that of the four already-formed loops shown in 25 Figs. 5 to 7, inclusive, or those shown in Fig. 4.

Due to the presence of the interposed portion 24 of element 20, the loops of the needle thread 31 are prevented from being completely drawn in. Accordingly, such loops do not draw the bobbin thread up to and against the body of the fabric work piece in customary fashion, but rather to the contrary such loops are merely drawn taut around the bobbin thread and the interposed portion 24 of the element 20, and the 30 bobbin thread lies within said loops parallel to and held against the portion 24 of element 20 by such loops. As the work is gradually continuously fed in a direction generally towards the rear with respect to the position of the presser- 40 foot 2, that is, in a direction extending from toe towards heel of said presser-foot, the loops and bobbin thread are gradually successively fed off of the free end of portion 24 of element 20, with the accompanying engaged bobbin thread. After 45 leaving the free end of portion 24 of element 20, the bobbin thread lies loosely in the line of slack stitches with such thread passing through the successive needle thread loops.

It will of course be understood that if the element 20 is formed of a rod of cylindrical stock, it, including its portion 24, will have a very definite diameter; and if formed of noncylindrical stock, such portion 24 will have a very definite vertical thickness. It will be understood 55 that the diameter or the vertical thickness, as the case may be, of the portion 24 of element 20, and the relative vertical location of portion 24 of element 20 with respect to the throat plate 23, will, within limits, be determinative of the 60 amount of slack ultimately present in the needle thread loop stitches. Thus an increase in the thickness or diameter of the portion 24 of element 20 and/or a lowering of the vertical position of such portion 24 with respect to the work 65 on throat plate 23 will result in the needle thread loops being formed of greater size, and, accordingly, in slackier stitching; while a decrease in such thickness or diameter and/or a raising of the vertical position of such portion 24 with respect to the work on the throat plate 23 will result in the needle thread loops being formed of smaller size, and, accordingly, in less slack or tighter stitching. It is thus apparent, that 70 two factors are present which may be possibly 75

varied, to wit: (1) the diameter or thickness of portion 24 of element 20; and (2) its vertical position with respect to the work on the throat plate 23. Within limits, which I will shortly point out, variation may be effected in either or both of, and/or adjustment may be effected between, these possible variable factors in order to make the ultimate needle thread loops of desirable, suitable size and slackness. Since, as will be readily understood, the final width of the ornamental stitched open work which I produce between the fabric work pieces being joined by such stitched open work will depend upon the length of thread in the needle thread loops, to wit: upon the size and slackness of such loops, it of course will follow that a suitable final width of the stitched open work may be arranged for by providing a diameter or thickness of portion 24 and a vertical position therefor which will yield needle thread loops of desired size and slackness. Turning to the aforementioned limits of possible variation, it should be understood that the portion 24 of element 20 must at all times be prevented from contacting and interfering with the presser-foot 2, and thus such portion 24 should not rise or lie above the upper surface of the throat plate 23. Further, it should be understood the portion 24 of element 20 must always be far enough above the rotary hook 5, that contact and interference of such portion with said rotary hook is avoided. It will be clear, therefore, that the highest possible vertical position of portion 24 is limited by the presser-foot, and that the lowest possible position thereof is limited by the external surface of the rotary hook 5. Likewise, the diameter or thickness of the portion of element 20 must always be large enough so that such portion 24 is sufficiently strong, that it may not be easily broken off from the bobbin case holder and, on the other hand, not so large that the same will interfere with the action of the needle, the proper formation of the loops of the needle thread, or render it impossible to readily and practically support and carry the said element 20 on the bobbin case holder. It will be clear, therefore, that the smallest diameter or thickness of portion 24 will be that which by a reasonable margin of safety is sufficient to eliminate all danger of portion 24 of element 20 being broken; and, the largest diameter or thickness will be that which will not interfere with the action of the needle, the proper formation of the loops of the needle thread, nor yield a portion 24 which is either impossible or difficult to readily support and carry on the bobbin case holder.

It will, of course, be understood that the line of slack stitch formed, with my construction, through, and to join the two fabric work pieces 60 29 and 30, will be usually preferably taken a relatively short distance in from the edges of the said pieces of fabric being thus joined, and, accordingly, relatively small selvages will, on each piece, extend out from the line of slack stitch 65 and lie between such line of slack stitch and the most adjacent fabric edges.

Turning next to the modified embodiment that I show in Figs. 8 to 10, inclusive, it will be observed that I provide, in said embodiment, an appropriately shaped and curved upper flange 33 arising from the outermost face of the bobbin case holder 7, which flange, whether integrally carried by or suitably secured to such bobbin case holder, is so shaped and configured that it clears 75 all moving parts of rotary hook 5. Carried by

this flange 33, substantially at the highest point on its top edge, to wit: substantially at the middle of such top edge, I provide a finger 34, which preferably is formed integral with the said flange or otherwise suitably secured thereto. This finger 34, it should be understood, is located in a position similar to that of portion 24 of element 20, and this finger is intended to serve the same purposes and provide the same functions as does the portion 24 of element 20. However, in this modified embodiment of my invention, a number of added advantages are attainable. Thus, as will be readily appreciated, both the finger 34 and element 20 are relatively slim compared to the size of the bobbin case holder 7, that is, the thickness or diameter of the stock thereof, and, accordingly, the cross-sectional area of such stock is relatively small compared to the size of the bobbin case holder 7. Thus, it follows that, by the employment of the finger 34 surmounted 20 on flange 33, there is, in the embodiment of Figs. 8 to 10, inclusive, an appreciable smaller vertical height of the slimmest element, that is, the finger element 34 is secured to the flange 33 by a slim element of less vertical height than the portion of element 20 which joins the portion 24 thereof with the bobbin case holder at the midtop of depression 12; and, accordingly, the finger 34 is more secure against risk of being possibly broken away during use than is the portion 24 of element 20, or any other portion of the element 20. Moreover, the finger 34 being carried by the bobbin case holder by a flange, the joinder of such flange to the bobbin case holder is over a surface which is relatively much greater in area 35 than the surface where the root of element 20 joins the bobbin case holder at the midtop of depression 12. The result of these features is that the finger 34 and flange 33 provide a structure which is relatively much stronger and more 40 rugged, and, accordingly, more secure against risk of possible breakage during use, than that of the element 20. Next, the flange 33, arising, as hereinbefore stated, from the outermost face of the bobbin case holder 7, instead of from the midtop of the depression 12, such flange at the level of the outermost surface of rotary hook 5 already stands out therefrom quite a bit, with the result that the necessity hereinbefore mentioned of providing an initial bend in element 45 20, such as bend 21, is, in the embodiment of Figs. 8 to 10, inclusive, substantially eliminated, and, accordingly, the flange 33 can be provided with a deeper curve or bend 33a of greater 50 "flare," with the result that the finger 34 for a great portion of its rearward extending length is thereby brought horizontally closer to the line of action of the needle, and, accordingly, lies in a horizontal direction more closely parallel to the line of slack stitch which is formed by the 55 machine. This feature in turn means that a greater length of the finger 34 lies in the most desirable effective horizontal position relative to the needle and the line of stitch, and, further, means that a throat plate 35 having uniformly 60 rectangular openings 36 may be employed in place of a throat plate, like the throat plate 23, which has, as hereinbefore indicated, an irregular-shaped opening 28 therein. Still further, the flange 33 provides an added smooth guiding surface for the needle thread 31 upon retraction of the loop after the discharge thereof from the beak 6.

Since, however, somewhat more metal is employed in the flange 33 of this embodiment, and 75

since lightness in weight is desirable, the flange 33 may be provided with an opening 37 therethrough, which will act to subdivide such flange into the arched flange arms 37a and 37b, and which further will provide a clearance space, which will insure definite certainty that the needle side of the needle thread loop, upon passing through the depression 12, will meet with no obstructive interference at the uppermost portion of said depression 12.

It will also be appreciated that with appropriate bending of my element 20 and with suitable configuring and constructing the same, a throat plate such as the throat plate 35 instead of the throat plate 23, might be used in conjunction therewith; that is, an element such as my element 20 might be so shaped and constructed that the same might be used in conjunction with a throat plate having irregular rectangular openings therein. However, I believe that this may not be as conveniently done with an element such as my element 20 as with my flange and finger construction, 33 and 34 respectively, shown in my embodiment in Figs. 8 to 10, inclusive. I believe that this necessarily is due to the fact that a small element, such as my element 20, is necessarily not as readily susceptible to the formation therein of suitable bends as is the finger and flange construction that I show in Figs. 8 to 10, inclusive. It should, however, be understood that I do not desire to be in any way limited as to the particular shape or type of throat plate openings in conjunction with which my slack stitch finger elements may be herein disclosed, but rather desire and intend that this disclosure cover such slack stitch finger irrespective of what may be the shape of the throat plate openings in conjunction with which it may be found most desirable to use the same, with the understanding, of course, that such slack stitch finger will be suitably shaped, configured and constructed to provide the desired function and result, when used with its throat plate.

I next desire to point out, that in all embodiments, the feed dog 25 employed is of substantially conventional construction with the exception that the portion 24 of element 20, or finger 34, each of which lies substantially in the plane of the throat plate, necessarily results in a reduction in the number of serrations or teeth in order to provide space and room for the slack stitch finger and/or because of the type and shape of the particular throat plate openings required. Thus, the position and shape of the slack stitch finger will have a material bearing upon the number of serrations or teeth that can be provided in line with the longitudinal axis of such finger. Further, a comparison of the throat plate 23 of Fig. 3 with the throat plate 35, of Fig. 10 will show that an irregular-shaped throat plate opening, such as the opening 28, may necessitate the omission of certain serrations or teeth in the feed dog serration or tooth rack furthest to the left, while the presence of regular rectangular throat plate openings, such as the opening 36, do not necessitate such omission; and, accordingly, in the latter case, the number of serrations or teeth on the serration or tooth rack furthest to the left may be made equal, or substantially equal, to the number of serrations or teeth on the rack thereof furthest to the right.

It, of course, will be readily appreciated that maintaining the number of serrations or teeth on the rack furthest to the right equal to the number on the rack furthest to the left, accom-

panied by a minimum of reduction in the number of serrations or teeth on the center rack, tends to insure the most smooth, uniform, even and direct feed of the work. Accordingly, further advantage is to be found in the embodiment shown in Figs. 8 to 10, inclusive, in that my stitch finger there lies substantially in line with the center of the middle serration or tooth rack of the feed dog 25 and as close as possible to the line of slack stitch and the line of action of the needle; with the result that the throat plate of such embodiment may have regular rectangular openings and the feed dog 25 may have side serration or tooth racks each having an equal number of serrations or teeth and a minimum of reduction in the number of serrations or teeth in the center rack with attendant advantage, as hereinbefore pointed out, in the feed of the work being stitched.

Having thus described the construction of the mechanisms I have shown in Figs. 1 to 10, inclusive, it will be understood that I employ the same as aforesaid to stitch together two fabric portions, to wit, an upper portion 29 and a lower portion 30, with a line of slack stitch. The work leaving this single needle sewing machine, that I have disclosed, has stitching like that shown to the left of the free end of the portion 24 of element 20, in Fig. 4 of the drawings.

Accordingly, it will be understood that the constructions which I have disclosed attain the objects of this invention, since they may be employed to readily unite fabric portions by a line of slack stitch, which, if, when and as desired, may be readily converted into practical, rugged, useful and desirable ornamental stitched open work, such, for example, as and by the method and means, respectively disclosed in and by my hereinbefore mentioned respective co-pending divisional applications, or in other suitable fashion.

It, accordingly, will be understood from all of the foregoing that by the employment of my invention, which I have herein disclosed, fabric pieces may be joined by a line of slack stitching, which, if and when desired, may be readily converted into highly ornamental stitched open work of desirable character.

From the foregoing, it will be obvious that, while I have described my invention in connection with certain machine constructions, my invention might with equal advantage be employed with other constructions. Thus, for example, my finger, the utilization of which results in slack stitching, might be embodied in different types of sewing machines. Likewise, it is conceivable that other modifications and/or variations might be found desirable and/or advantageous.

Inasmuch, therefore, as many changes may be made in the above constructions, and many apparently widely and different embodiments within the scope of the invention may be made without departing from the spirit and scope thereof and inasmuch as my invention may reasonably be used for many purposes, it is intended that all matters hereinabove contained or shown in the accompanying drawings shall be interpreted as illustrative and not as in any sense limiting.

The following claims are intended to cover all generic and specific features of the invention described.

What I seek to secure by and claim for United States Letters Patent is:

1. As a new article of the type described for use beneath a sewing machine throat plate, a stationary bobbin case holder and a bent finger car-

ried at the top thereof; said finger being so constructed and arranged that the free end and the portion adjacent the free end thereof lie substantially in the general plane of the throat plate.

5. 2. In a work sewing machine of the type described having a thread-carrying needle, a bobbin case holder for holding a bobbin case and bobbin, a rotary hook, and a hook drive shaft for driving said hook upon and about said bobbin case holder, the combination of a slack stitch finger mounted on and carried substantially at the top of said bobbin case holder, about a portion of which finger the needle thread will be successively looped upon successive rotations of the rotary hook, and means for advancing the work gradually away from the free end of said stitch finger.

3. The structure recited in claim 2, characterized in that means are provided for guiding the needle thread into looped position about a portion of said stitch finger.

4. A bobbin case holder, a shaped flange formed on the outermost face thereof substantially at the top thereof and an integral hook finger carried by said flange substantially at its upper free end.

5. As a new article for use in a sewing machine wherein fabric pieces are advanced through a stitch position where they are provided with slack stitching, a bobbin case holder having a stationary slack stitch finger secured thereto and extending parallel to the direction of advance of the fabric pieces.

6. In a work sewing machine having a thread-carrying needle, the combination of a bobbin case holder, means for forming the needle thread into

a loop and stationary means secured to the bobbin case holder for maintaining the needle thread loop, when formed, from being drawn taut against the work.

7. In a sewing machine for uniting work pieces with a line of slack stitching, said sewing machine having a throat plate, means for advancing the work along the upper surface of said throat plate, a thread-carrying needle adapted to reciprocate up and down along a single line of movement for intermittently piercing the work upon advance thereof, and a thread-carrying bobbin beneath said throat plate, the combination of a stationary finger secured to said sewing machine beneath the throat plate and so positioned that it extends substantially parallel to the throat plate and generally in the direction of work advance, and means for engaging the thread carried by the needle each time after the needle has pierced the work, forming such thread into a loop and crossing a limb of such loop over the bobbin thread and said stationary finger.

8. The structure recited in claim 7, characterized in that the under surface of the stationary finger is positioned equally distant from the upper surface of the throat plate throughout the length of such part of such finger as is effective to cause slack stitching.

9. The structure recited in claim 2, characterized in that the portion of the finger about which the needle thread is successively looped is of a length sufficient to hold thereon a number of formed needle thread loops, and that throughout the length of such portion the finger is of substantially uniform dimensions.

ANTONIO TURRISI.
